UNITED STATES PATENT OFFICE.

HARRY A. DOUGLAS, OF BRONSON, MICHIGAN.

CIRCUIT-CONTINUING DEVICE.

Original application filed January 5, 1921, Serial No. 440,436. Divided and this application filed December 3, 1923. Serial No. 678,210.

My invention relates, generally speaking, to circuit continuing devices and is inclusive of a metallic shell, a mounting therefor, a clip secured to the shell, this clip being assembled with the mounting, and wire attaching means provided upon the outer end of said clip.

I will explain my invention more fully by reference to the accompanying drawings 10 showing the preferred embodiment thereof and in which Fig. 1 is a longitudinal sectional view; Fig. 2 is a rear end view of the structure shown in Fig. 1; Fig. 3 is a sectional view on line 3—3 of Fig. 1; Fig. 4 is 15 a perspective view of an element that takes part in assembling portions of the structure; Fig. 5 is a sectional view of a part of the device shown in Fig. 1, taken on line 5—5; and Fig. 6 is a sectional view on line 20 6—6 of Fig. 1.

Like parts are indicated by similar characters of reference throughout the different figures.

By reason of the illustrated construction, 25 the mounting sleeve 1 may be metallic. This sleeve is provided with a flange 2 carrying sleeve rivets 3 that assemble the insulating mounting plate 4 with the base of the mounting sleeve. These rivets also 30 serve to permit of the passage of mounting screws through the base flange of the mounting sleeve into some suitable support, such, for example, as the dashboards of automobiles. The metallic shell 5 is surrounded 35 and substantially housed by the mounting sleeve, this metallic shell being suitably assembled with the mounting plate or insulating body 4 that fixedly unites the rear ends of the shell and sleeve. The forward 40 end of the shell is formed with bayonet channels 6 which are adapted to receive bayonet projections 7 carried by the base of the incandescent lamp bulb 8, such lamp base constituting a contact carrier. The bulb of 45 the lamp projects forwardly beyond the shell and sleeve and in order that the passage of light therefrom may be limited to a definite path the bulb is partially enclosed by a cowl 9 which is mounted upon the reduced forward end of the shell 1, the base 50 of the cowl engaging the shoulder formed upon the shell where the reduced portion is connected with the balance of the shell.

A single pole structure is illustrated in 55 which case there is but one lamp base con-

tact 10 upon the inner face of the lamp base and but one forwardly spring pressed contact 11 engageable with the contact 10, one terminal of the lamp filament being connected with the metallic sheath that engages the metallic sleeve 5 which is in grounded connection with the source of current that supplies the lamp. The shell 5 is desirably fixedly assembled with the insulating body 4 by means of clips 13 having opposite notches 14 that receive ears 15 struck outwardly from the shell whereby the base of the shell is held against the inner face of the plate 4 except where the shell is formed with rearwardly projecting 60 tongues 16 that extend through the plate 4 to prevent the shell from turning and to take part in fixing the angular relation of the shell to the plate. Each clip is formed with an angular ear 17 that engages the 65 rear face of the plate 4 to complete the assembly of the plate and shell. Where the structure is a so-called single pole structure one of the clips is provided with a rearward continuation 18 having threaded holes 19 70 that receive the binding screws 20 that serve to connect the current conducting wire with the clip provided with the extension whereby the shell connected with the clip 75 may be grounded. There is a flat terminal plate 21 that carries contact 11 in riveted connection therewith at the front end of the plate, the rear end of the plate being formed with a threaded hole that receives a binding screw 22 for connecting the plate and the contact thereon in circuit. There is a 80 metallic sleeve 23 for guiding the plate 21 which is movable longitudinally of the sleeve 23 enclosing it. The rear end of the sleeve 23 is formed with flanges 24 85 that define an annular channel between which the mounting plate 4 is gripped. A coiled spring 25 surrounds the sleeve 23, being compressed between the corresponding contact 11 and the forward flange 90 95 24. The contact 11 is thus forwardly spring pressed into engagement with its complementary contact 10 when the contact carrier carrying such complementary contact is fully assembled with the forward end of 100 105 the shell 5.

While I have herein shown and particularly described the preferred embodiment of my invention I do not wish to be limited to the precise details of construction shown 110

as changes may readily be made without departing from the spirit of my invention, but having thus described my invention I claim as new and desire to secure by Letters Patent the following:

A circuit connector including a metallic shell; a mounting therefor; a clip secured to the shell by means of an ear which is

struck from the shell, this clip being assembled with the mounting; and wire attaching means provided upon the outer end of said clip.

In witness whereof, I hereunto subscribe my name this second day of October, A. D., 1923.

HARRY A. DOUGLAS.
